UNITED STATES PATENT OFFICE.

JOHN W. COCHRAN, OF NEW YORK, N. Y.

IMPROVEMENT IN CAR-AXLE BOXES.

Specification forming part of Letters Patent No. 21,943, dated November 2, 1858.

To all whom it may concern:

Be it known that I, JOHN W. COCHRAN, of the city of New York, in the State of New York, have invented certain Improvements in Axle-Boxes for Cars; and I do hereby declare that the following is full and exact description of the same, reference being had to the accompanying drawings, and to the letters and marks thereon.

Of the drawings, Figure 1 is a side view, in which part of the means are shown as if the side of the box had been removed; Fig. 2, a back or wheel end view; Fig. 3, a plan or bird's-eye view, in which certain parts are shown as in a sectional view; and Figs. 4 and 5, a side and end view of a packing ring or collar to the axle.

In each of the figures like marks and letters indicate like parts.

A marks the outside or shell of the box; B, the packing-disk or stuffing-box; C, the lubricating cell or well for holding the lubricating-liquid; D, the axle; e, the packing of felt, leather, hide, or gutta-percha; e', a recess in the collar for packing between the collar and the axle; f, the joint between the shell of the box A and disk B; g, the door of the box; h, the feed-hole; j, bolts; j', slots in the ears or lugs of the box; i, a set-screw for elevating and adjusting disk B. The sliding collar on the axle is marked a and the slit in it a' for the pin a'' of the axle.

The first feature of my improvement arises from the ring or collar a. Its position upon the axle is shown by red lines in Fig. 3. It will be seen that it fits around the axle, and is so held to the axle by the pin or screw a'' as to be turned or rotated with the axle, but by virtue of the slit a' does not move with the axle in its lateral play. A recess is in the inner surface of this ring (marked e') for packing between it and the axle. The outer end of the collar is thickened for this recess e', and as this thick part extends outwardly it is tapered and a groove or recess is formed in the tapered circumference n. This tapered extension and recess n gives facilities for packing and aids in making a tight joint. It will be seen that the packing lying between the ta-

pered or beveled surface of the collar's extension and the beveled edge of the ring d is clamped at an angle to the other portion of the packing. It will also be seen that the packing e extends around the collar within the extension and around the axle beyond the collar. This arrangement admits of the ready and complete tightening of the packing by the screw-bolts j, j. These bolts j, j are the only bolts used and serve to keep the various parts of the box in position and to tighten all the packing.

The second feature of my improvement depends upon the arrangement of various parts of the box with the view of accommodating them to the wear of the brasses on the top of the bearing. It will be perceived that the lubricating-roller b is attached by the spring-shaft c to the door g, and that the door g, by the bolts j, j, is attached to the disk B. Recesses in the ears and lugs of the box A allow of the movement of these bolts. A set or adjusting screw i underneath the disk adjusts the disk, so that by simply slackening the bolts j, j' and turning the screw i the lubricator, door, disk, packing, and bolts are all readily moved and adjusted. The lubricator is therefore always on the same line in respect to the shaft which sustains it and in respect to the axle, and the door and the disk are also in the same relation to the ends of the box.

Having thus fully and clearly set out the construction and operation of my invention, what I claim as new, and desire to secure by Letters Patent, is—

1. The sliding collar a, constructed and arranged upon the axle and in relation to the packing and the box, as herein set forth.

2. The arrangement of the lubricator, door, disks, packing, follower, and bolts, as herein described, whereby the whole may be adjusted to the bearing-brasses, as herein set out.

This specification signed this 2d day of October, 1858.

J. W. COCHRAN.

Witnesses:

JOHN BISNY,
T. T. EVERETT.
